UNITED STATES PATENT OFFICE.

HORACE W. BEEBE, OF NEW HAVEN, CONNECTICUT.

VEHICLE-LAMP.

No. 925,676.

Specification of Letters Patent.

Patented June 22, 1909.

Application filed April 19, 1909. Serial No. 490,952.

To all whom it may concern:

Be it known that I, HORACE W. BEEBE, a citizen of the United States, residing at New Haven, in the county of New Haven and State of Connecticut, have invented a new and useful Improvement in Vehicle-Lamps, and do hereby declare the following, when taken in connection with the accompanying drawings and the numerals of reference 10 marked thereon, to be a full, clear, and exact description of the same, and which said drawings constitute part of this specification, and represent, in—

Figure 1 a front view of a lamp constructed in accordance with my invention, showing means for temporarily suppressing the action of the reflector. Fig. 2 a side view partially in section of the same. Fig. 3 a side view on an enlarged scale of the screen in its 20 depressed or closed position. Fig. 4 a rear view of the screen in its raised or open position. Fig. 5 a top or plan view of the screen in its closed position.

This invention relates to an improvement 25 in vehicle lamps of the search light type in which provision is made for temporarily suppressing the action of the reflector in a general way like the lamp shown and described in the application of John K. Punderford 30 filed January 18, 1909, Serial No. 472,896.

The object of the invention is a simple arrangement of means for temporarily suppressing the action of the reflector; and the invention consists in the construction herein- 35 after described and particularly recited in the claims.

As in the application above referred to, I employ a tube 2 which is arranged in line with, and in rear of the burner 3. The rear 40 of the tube is cut away forming a vertically arranged slot the edges of the upper end forming cam surfaces 4 and 5. Mounted in the tube is a vertically movable rod 6 which may be raised and lowered by any convenient 45 means. Hinged to this rod are two semi-circular leaves 7 and 8, and mounted on the rod is a spiral spring 9 the ends 10 and 11 of which project outward to engage with the rear surfaces of the leaves 7 and 8. The two

leaves when opened form a circular disk 50 which will stand between the burner and the reflector 12 and so temporarily suppress the action of the reflector; and the springs will hold the leaves in the open position. When it is desired to retract the screen or disk the 55 rod 6 will be drawn downward and the edges of the disk riding on the cam surfaces 4 and 5 will fold the disks together and allow them to be drawn downward into position in line with, and in rear of the burner. To facilitate 60 folding of the leaves they may be each formed with a slight corrugation 13 at their lower edges which will ride over the cam surfaces 4 and 5 and reduce the friction in the folded movement.

It will be understood that the rod is moved from a convenient point in the vehicle, and so that when two vehicles are approaching each other, the rod may be raised to open the screen between the burner and the reflector 70 so as to temporarily suppress the action of the reflector. As in the case before referred to, the burner is not affected and the light therefrom will be sufficient to enable one 75 driver to see the course of the other.

I claim:—

1. In a lamp, the combination with a burner and reflector, of a tube located between the burner and reflector, a vertically movable rod in said tube, two semi-circular 80 disks hinged to said rod and adapted to be folded rearward into line with said burner.

2. In a lamp, the combination with a burner and reflector, of a tube located between the burner and reflector, said tube 85 formed with a vertically arranged slot, the edges of the upper portion of which are of cam shape, a vertically arranged rod in said tube, leaves hinged to said rod, and a spring mounted on said rod and normally tending 90 to open said leaves.

In testimony whereof, I have signed this specification in the presence of two subscribing witnesses.

H. W. BEEBE.
